Primary Examiner — Cynthia Ramirez(74) *Attorney, Agent, or Firm* — Davis & Bujold, P.L.L.C.**CLAIM**

The ornamental design for a tubular pallet member, as shown and described.

DESCRIPTION

FIG. 1 is a side elevation view of the tubular pallet member the opposite side being a mirror image thereof;

FIG. 2 is a left end elevation view of the tubular pallet member of FIG. 1, the right end being a mirror image thereof;

FIG. 3 is a top plan view of the tubular pallet member of FIG. 1; and,

FIG. 4 is a bottom plan view of the tubular pallet member of FIG. 1.

The broken lines shown in FIGS. 3 and 4 are included for the purpose of illustrating only and do not form any part of the claimed design.
